SLIPPER

William M. Scholl, 213 W. Schiller, Chicago 10, Ill.

Filed May 27, 1963, Ser. No. 75,090

Term of patent 14 years

(Cl. D7—7)

FIG. 1 is a perspective view of a slipper embodying my new design as it appears when in wearing position;

FIG. 2 is a top plan view of the slipper shown in FIG. 1 as it appears in relaxed position;

FIG. 3 is a bottom plane view thereof; and

FIG. 4 is a side perspective view thereof, the side opposite thereto being substantially similar.

I claim:

The ornamental design for a slipper, substantially as shown and described.
